TAPE FEEDING MECHANISM

Thomas H. North, St. Paul, Minn., assignor to
Trans-Lux Movie Ticker Corporation, New
York, N. Y., a corporation of Delaware

Application March 5, 1936, Serial No. 67,281
Renewed January 11, 1939

10 Claims. (Cl. 271—2.3)

This invention relates to an improvement in a feed mechanism for news printing tickers of the type ordinarily used for printing stock quotations, or for any other type of tickers. The feed mechanism is particularly adapted for use with tickers in general used in combination with projecting apparatus, to feed the tape issued by the ticker past the projecting apparatus.

Apparatus has been previously devised for drawing tape from a ticker past a projecting device. Due to the fact that the tape is not issued from the ticker at a constant speed, but is rather issued intermittently, some means must be provided to move the tape past the projecting means at the same speed at which it comes from the ticker. In the past, this means has generally consisted in a motor controlled by a switch operated by the ticker, or by action of the tape adjacent the ticker, to start and stop the motor driving the tape pulling mechanism according to the speed of the ticker operation.

It is an aim of the present invention to provide a feeding mechanism for the tape projecting means which will move the tape intermittently. To accomplish this aim without any means for stopping and starting the motor, or without any means of varying the speed of the motor is one of the objects of my invention.

It is a purpose of my invention to provide a tape feeding means operable by a constant speed motor which is continuously in operation to move the tape intermittently. This result is accomplished by means of a clutch operated by the action of the tape to pull the tape until it catches up to the ticker. The clutch then holds the tape stationary until the ticker once again gets ahead of the projecting means, whereupon the movement of the clutch feeds more tape past the projecting means. This clutch includes a positive mechanical drive, and does not comprise merely a friction slip clutch.

The clutch which I employ is of a planetary gear type in which the driving force from the motor may be transmitted either to a pulley over which the tape passes, to pull the tape past the projecting device, or to a drum which acts merely as an idle wheel. The forces are so arranged as to ordinarily transmit the power to the idle wheel, until a brake is applied to this wheel, whereupon the pulley is rotated. The brake is applied by the tape issuing from the ticker.

These and other objects and novel features of my invention will be more fully and clearly set forth in the following specification and claims.

In the drawings forming a part of this specification:

Figure 1 is a top plan view of a tape projecting mechanism, with my clutch mechanism attached thereto.

Figure 2 is a front elevation view of the projecting mechanism and tape feeding mechanism illustrated in Figure 1.

Figure 3 is a side elevation view of the projecting mechanism with the tape feeding mechanism applied thereto.

Figure 4 is a front view of the mechanism illustrated in Figure 2, with the front wall of the projector removed.

Figure 5 is a side view of the mechanism as illustrated in Figure 3 of the drawings, with the side of the casing removed, and showing the lenses in cross-section.

Figure 6 is a top plan view of the tape feeding mechanism, showing this apparatus more in detail.

Figure 7 is a front elevation view of the tape feeding mechanism illustrated in Figure 6.

Figure 8 is a side elevation view of the tape feeding mechanism shown in Figures 6 and 7.

Figure 9 is a cross-sectional view on the line 9—9 of Figure 6, showing the clutch feed drive in detail.

Figure 10 is a cross-sectional view on the line 10—10 of Figures 9 and 6, showing the clutch feed drive of Figure 9.

Figure 11 illustrates sectionally through the center of the clutch mechanism, the arrangement of gearing therein.

Figure 12 illustrates more in detail the arrangement of gears in the clutch mechanism, and is a section taken on the line 12—12 of Figure 11.

The tape feed mechanism A is for the purpose of feeding news print tape 10 from the ticker B (illustrated in Figures 2 and 4) through the projecting apparatus C. The tape 10 issues from the ticker B, and extends over the lens 11 of the projecting apparatus C. Light from the projector lamp 12, directed through the lenses 13, is reflected by the reflector means 14, through the lenses 11 and 16 against the reflector mirrors 17, which in turn reflect the image against the screen D, upon which it is observed. The screen D may be formed of ground glass or the like so as to be readily readable upon the front surface 18. Idle rollers 19 mounted on either side of the projecting mechanism C, act to guide and control the position of the tape 10. Suitable ventilating openings 20, and a heat releasing ventilating opening 22.

over the projector lamp 12 maintains a safe temperature within the projecting mechanism C.

To feed the tape over the projecting apparatus C, I provide the feed mechanism A, secured by means of a bracket 23 to the outside of the housing 24 enclosing the projecting apparatus C. This mechanism C is connected mechanically to the driving motor 25 which is enclosed within the housing 24, to decrease the noise, and to improve the appearance of the unit.

The motor 25 is secured in position within the housing 24 in any suitable manner, as by the bolts 26. The motor drive shaft 27, Fig. 5, is connected by a coupling 28 to a shaft 29 extending through a wall of the housing 24 and journalled in a casing 30. The casing 30 is attached to the outside of the housing 24 by means of the bracket 23 as previously described. The shaft 29, on the portion thereof between the bearings 32 of the casing 30, bears a worm 33 in mesh with a worm wheel 34 mounted on the shaft 35 extending at right angles to the shaft 29. The shaft 35 extends from the casing 30, being journalled at the points 36 within this casing, to operate the clutch E forming a part of the feed mechanism A at a speed reduced from that of the motor 25.

The shaft 35 forms a journal for a disc 37 having a circumferential flange 38 thereupon. This disc 37 is free to rotate with respect to the shaft 35. Upon the shaft 35, I secure the pinion 39, rotatable with the shaft 35. Upon the end of the shaft 35 beyond the pinion 39, I mount a roller 40, freely rotatable with respect to the shaft 35. A cotter pin 42 holds this roller in position on the shaft 35.

On opposite sides of said shaft 35, a pair of pins 43 extend into the end of the roller 40 adjacent the disc 37. Upon these pins 43, I mount a pair of idle pinions 44, forming planet wheels, and in mesh with the pinion 39 on the shaft 35. An internal gear 41 is secured tightly within the flange 38 of the disc 37, and meshes with the idle pinions 44, thus forming a planetary gear system.

A brake is provided to bear against the outside 45 of the flange 38 to stop this gear 41 from rotation. This brake, designated 45, comprises a brake shoe 46 mounted upon an arm 47 which is pivotally mounted at 48 to the casing 30. The free end of the arm 47 is connected by a flexible strip 50 49 extending up over a pulley 50 illustrated in Figure 4. This pulley 50 is pivotally mounted within the housing 24, and the arm 47 extends through a slot in this housing 24. The flexible strip 49 extends a partial revolution around the pulley 50, and is secured at 52 thereto. An arm 53 is also secured to the pulley 50 to rock the same. This arm 53 extends through the opposite wall from that through which the arm 47 extends, and is provided with an idle pulley 54 on 60 the end thereof. The pulley 54 rests upon the tape 10 intermediate the projector C and the ticker B, and swings up or down, depending upon the length of tape between the ticker and the projecting apparatus.

To provide a tension on the tape 10 so as to provide a virtually constant pull for the motor 25 when it is operating to pull the tape, I provide an arm 55 pivoted in an ear 56 on the top of the housing 24. A bearing block 57 is mounted on this arm 55 to press the tape 10 against the housing 24. A slideable weight 58 on the arm 55 is adjustable to vary the tension on the tape. As may be seen, the weight of the bearing block 57 and the arm 55, with its weight 58, tend to stop

the tape from movement, and create a tension in the tape 10.

To hold the tape 10 firmly against the roller 40, I mount a bracket 59 on the housing 30, and pivotally mount a shaft 60 in this bracket 59. A bell 5 crank lever 62 is pivotally mounted at its intermediate pivot to rotate with the shaft 60. One arm of the lever 62 is bifurcated to accommodate the bearing wheel 63 which is pivoted between the spaced ends of this lever arm. The other arm 10 64 of the lever 62 forms a finger engaging end by means of which the lever 62 may be easily pivoted.

Some means is provided for holding the bearing wheel 63 against the roller 40 to hold the tape 10 therebetween with spring tension. This means 15 is shown as comprising a plunger 65 having a tapered end 66 which is urged by a spring 67 against the shaft 60. The plunger 65 is mounted in a cylindrical passage in the bracket 59. The shaft 60 is provided with depressions 68 into 20 which the plunger 65 may extend, to hold the bearing wheel 63 either against the roller 40 or pivoted away from the roller. As the diameter of the wheel 63 is slightly large to permit the plunger to extend to the bottom of the depressions 25 68 when the wheel 63 is pivoted against the roller 40, there is provided a spring force urging the wheel 63 against the roller 40.

In operation, the tape 10 is threaded into operative position from the ticker, under the pulley 30 54, over the guide rollers 19 on either side of the light aperture over which the tape passes, and between the roller 40 and the bearing wheel 63. The motor 25 is then turned on. If the loop 70 in the tape 10 is sufficiently large, the arm 53 35 pivots downwardly rotating the pulley 50. This acts to wind a part of the flexible strip 49 upon the pulley 50, drawing the arm 47 upwardly. The arm 47 pivots about its pivot 48, urging the brake shoe 46 against the flange 38 of the disc 37.

Stopping the rotation of the disc 37 acts to stop the internal gear 41 secured therein. Thus, the rotation of the motor driven shaft 35 and the pinion 39 secured thereon acts to move the idle gears or pinions 44 as planet gears, their centers 45 moving in a circular path. As these centers are mounted upon pins 43, however, set into the roller 40, this roller 40 is caused to rotate by the motor 25 when the brake shoe 46 stops rotation of the flange 38 and disc 37.

When the ticker B ceases to operate, or operates more slowly than the tape 10 is fed by the tape feeding means A, the loop 70 diminishes in size. This causes the pulley 54 on the arm 53 to pivot upwardly, rotating the pulley 50. This unwinds 55 a portion of the flexible strip 49 from the pulley 50, and allows the free end of the arm 47 bearing the brake shoe 46 to pivot downwardly, releasing the brake shoe from the flange 38. Because of the fact that there is more leverage tending to 60 turn the disc 37 and flange than there is to turn the roller 40, the pinions 44 will be rotated by the central pinion 39 and will act upon the internal gear 41 to rotate the disc 37, the centers of the pinions 44 remaining stationary.

It may be seen that my feeding device operates intermittently in accordance with the movement of the tape from the ticker. The movement of the tape is not jerky, as the brake gradually contacts the flange 38, and causes the roller 40 to 70 slowly start into rotation.

In accordance with the patent statutes, I have described the principles of operation of my feeding mechanism; and while I have endeavored to set forth the best embodiment thereof, I desire 75

to have it understood that this is only illustrative of a means of carrying out my invention, and that obvious changes may be made within the scope of the following claims without departing 5 from the spirit of my invention.

I claim:

1. A tape feed mechanism including a rotatable driving means, means constantly rotating said driving means, a pair of rotatable driven means, either one of which is rotatable while the other remains idle, means for advancing the tape by one of said rotatable driven means, and means in engagement with the tape and sensitive to tension in the tape and operatively associated 10 mechanically with the other of said driven means for holding said other of said means stationary to drive the tape.

2. A tape feed mechanism including a constantly rotating driving means, a pair of rotatable driven means, means connecting said rotatable driven means to said driving means to drive either of said means while the other of said rotatable means remains stationary, and means in engagement with the tape and sensitive to tension in the tape and operatively associated mechanically 15 with one of said rotatable driven means for holding said one of said rotatable driven means stationary to cause rotation of the other of said rotatable means.

3. A ticker tape feed mechanism including a continuously rotating drive means, a clutch operated by said drive means having a continuous mechanical connection with said drive means, and means in engagement with the tape and sensitive to tension in the tape and operatively associated 20 mechanically with a part of said clutch for holding said part of said clutch stationary during continuous operation of said drive means.

4. A ticker tape feed mechanism including a continuously rotatable drive means, a tape advancing means, and a clutch interposed between said drive means and said tape advancing means having a continuous mechanical connection with said drive means and with said tape advancing 25 means and means in engagement with the tape and sensitive to tension in the tape and operatively associated mechanically with a part of said clutch for holding said part of said clutch stationary during continuous operation of said drive means.

5. A tape feed mechanism including a continuously rotatable driving means, a series of gears driven by said driving means, a tape feed roller driven by said gears, means supporting said gears 30 to permit said driving means to constantly operate while said feed roller remains stationary and means in engagement with the tape and sensitive to tension in the tape and operatively associated mechanically with a part of said supporting means to anchor said part of said supporting means in turn to release said feed roller.

6. A means for pulling a tape intermittently, including a constantly rotatable driving mechanism, a tape pulling roller for pulling tape and varying the tension of the pulled tape, a second rotatable member, said driving mechanism selectively driving said roller and said second member, and means in engagement with the tape sensitive to variations in the tension of the tape 35 and operatively associated mechanically with a part of said second rotatable member for stopping rotation of said second rotatable member to start rotation of said roller.

7. A tape feed mechanism including a continuously 40 rotatable driving element rotatable at a pre-

determined uniform speed, a tape pulling roller, a variable speed imparting clutch operatively associating said driving element with said pulling roller exclusively controlled by said clutch, said clutch including a rotatable clutch element when retarded operable to initiate the rotation of said tape pulling roller and when liberated and while picking up speed operable to initiate a gradual retardation of said tape pulling roller, a drum operatively associated with said clutch to control 45 said clutch, a brake-shoe positioned to engage and anchor or release said drum, and a lever operatively associated with said brake-shoe and having a portion thereof riding on the tape, said lever being responsive to deflections in the tape when slack is formed to actuate said shoe against said drum thereby to enable said drum to rotate and thereby cut out rotation of said tape pulling roller.

8. A tape feed mechanism including a tape pulling roller, a control device including a rotatable element operably associated with said roller 50 exclusively controlled by said device, said device when retarded initiating the rotation of said tape pulling roller and when liberated and while picking up speed initiating a gradual retardation of said tape pulling roller, a brake drum operatively associated with said control device, a brake-shoe positioned to engage and anchor or release said brake drum, and a lever operatively associated with said brake-shoe and having a part thereof riding on the tape, said lever being responsive to 55 deflections in the tape when slack is formed to actuate said shoe against said drum thereby to cause said tape pulling roller to be actuated, and in turn responsive to the dissipation of slack in the tape to actuate said shoe to release said drum to enable said drum again to rotate and thereby cut out rotation of said tape pulling roller.

9. A tape feed mechanism including a tape pulling roller, a variable speed imparting clutch operatively associated with said tape pulling roller, said clutch including a control device having a rotatable element when retarded operable to initiate the rotation of said tape pulling roller and when liberated and while picking up speed operable to initiate a gradual retardation of said tape 50 pulling roller, a brake drum operatively associated with said control device, a brake-shoe positioned to engage and anchor or release said brake drum, and a lever operatively associated with said brake-shoe and having a part thereof riding 55 on the tape, said lever being responsive to deflections in the tape when slack is formed to actuate said shoe against said drum thereby to cause said tape pulling roller to be actuated, and in turn responsive to the dissipation of slack in the 60 tape to actuate said shoe to release said drum to enable said drum again to rotate and thereby cut out rotation of said tape pulling roller.

10. A tape feed mechanism including a driving means, a tape pulling roller, a variable speed 65 imparting clutch operatively associating said driving means with said tape pulling roller exclusively controlled by said clutch, said clutch including a control device having a rotatable element when arrested operable to effect the prompt 70 start of said tape pulling roller and when liberated and while picking up speed operable to initiate a gradual retardation of said tape pulling roller, a brake drum operatively associated with said clutch to control the operation thereof, a brake- 75

- shoe operatively positioned to engage and anchor said drum or to release the same, a lever operatively associated with said brake-shoe and having a part thereof riding on the tape, said lever being responsive to deflections in the tape when slack is formed to actuate said shoe against said drum thereby to enable said driving means to ac-
- 5

tuate said tape pulling roller and in turn responsive to the dissipation of slack to actuate said shoe to release said drum to enable said drum again to rotate and thereby cut out rotation of said tape pulling roller.
